UNITED STATES PATENT OFFICE.

OLIVER L. BADGER, OF PLAINFIELD, NEW JERSEY, ASSIGNOR TO KERR ADJUSTABLE STRAP COMPANY, INC., OF NEW YORK, N. Y., A CORPORATION OF NEW YORK.

DESIGN FOR A METAL KEEPER FOR STRAPS AND OTHER LIKE DEVICES.

52,942.

Specification for Design.

Patented Feb. 4, 1919.

Application filed October 10, 1918. Serial No. 257,665. Term of patent 3½ years.

To all whom it may concern:

Be it known that I, OLIVER L. BADGER, a citizen of the United States, and resident of Plainfield, in the county of Union and State of New Jersey, have invented a certain new, original, and ornamental Design for a Metal Keeper for Straps and other like Devices, of which the following is a specification, reference being had to the accompanying drawing, forming part thereof, in which—

Figure 1 is a face view of a metal keeper

for straps and other like devices showing my new design;

Fig. 2 is a rear view of the same;

Fig. 3 is an edge view of the same; and

Fig. 4 is a side view of the same.

I claim:

The ornamental design for a metal keeper for straps and other like devices, as shown.

OLIVER L. BADGER.
